CLAIM

The ornamental design for an electrical insulator with integral circuit-parameter sensing features, as shown and described.

DESCRIPTION

FIG. 1 is a perspective view of an electrical insulator with integral circuit-parameter sensing features showing our new design;

FIG. 2 is a front elevational view thereof;

FIG. 3 is a rear elevational view thereof;

FIG. 4 is a left side elevational view thereof, the right side elevational view being a mirror image;

FIG. 5 is a top plan view thereof;

FIG. 6 is a bottom plan view thereof.
